CLAIM

The ornamental design for an infectious waste container
for use in hospitals and other health care facilities, as
shown.

DESCRIPTION

FIG. 1 is a perspective view showing the top, left side
and front of the infectious waste container container
for use in hospitals and other health care facilities showing
by design;

FIG. 2 is a right side elevation view thereof;

FIG. 3 is a rear elevation view thereof; and

FIG. 4 is a bottom plan view thereof.

*FIG. 1.**FIG. 2.**FIG. 3.**FIG. 4.*
